ATTORNEYS.

UNITED STATES PATENT OFFICE.

FRANCIS J. SCHMID, OF NEW YORK, N. Y.

DESIGN FOR COACH-LACE.

SPECIFICATION forming part of Design No. 12,418, dated August 16, 1881.

Application filed July 16, 1881. Term of patent 3½ years.

To all whom it may concern:

Be it known that I, FRANCIS J. SCHMID, of the city, county, and State of New York, have invented a new and Improved Design for Coach-Lace, of which the following is a specification.

The design is shown in the drawing by a face view.

The design relates to the surface ornamentation, by raised patterns, of coach-trimming lace.

10 A in the drawing is the lace or trimming material, having the raised design on its face.

The essential features of the design are the oval figures *a*, formed by crossed segments of circles interlaced to form a chain of oval links.

15 The lace is also formed with raised edges *b* *b*, which add to the ornamental appearance, but are not essential to the design.

Having thus described my invention, I claim as new and desire to secure by Letters Patent—

1. The design for coach-lace herein shown and described, which consists of a chain of oval links formed by interlaced crossed segments.
2. The design for coach-lace herein shown and described, which consists of the chain of oval links *a* and raised edges *b* *b* on the surface of the material.

FRANCIS J. SCHMID.
